INFANT NURSER HOLDER WITH DISPOSABLE CARTRIDGE REFILL

Michael C. Ritsi, 7950 SW. 16th St.,
Miami, Fla. 33155

Filed Feb. 22, 1972, Ser. No. 228,460

Term of patent 14 years

Int. Cl. D24—03
U.S. Cl. D83—8 R

FIG. 1 is a front view of an infant nuser holder with disposable cartridge refill, showing my new design;

FIG. 2 is a cross-sectional view taken substantially along the line 2—2 in FIG. 1;

FIG. 3 is a bottom view thereof; and

FIG. 4 is a cross-sectional view taken substantially along the line 4—4 in FIG. 2.

I claim:

The ornamental design for an infant nuser holder with disposable cartridge refill, substantially as shown.
